SENSITIZING AGENTS COMPRISING THE REACTION PRODUCT OF UREA-FORMALDEHYDE HYDROGEN PEROXIDE

Luther O. Young, Baltimore, Md., assignor to W. R. Grace & Co., a corporation of Connecticut
No Drawing. Filed Mar. 22, 1963, Ser. No. 267,321
5 Claims. (Cl. 149—46)

The present invention relates to improvements in explosives, and more specifically to improvements in chemical explosive compounds.

Explosives have become increasingly important articles of commerce. Civilian use extends to coal mining, metal mining, quarrying and non-metal mining, railway and other construction. While the military uses extend from small arms ammunition and high explosive shells to rocket propellants.

These varied uses require different kinds of explosives, ranging from the very low pressure explosives such as propellants, to the highest pressure military explosives. Between these two extremes, there exists an almost continuous distribution of conditions requiring explosives of all sorts of pressure and rate characteristics.

Considerable interest has developed in the area of sensitizing compounds for relatively insensitive explosives. There are many requirements which must be met by a sensitizing material. It must be capable of being blended with the explosive and be sufficiently stable for reasonable periods of storage. Furthermore, a sensitizing agent to be useful should be capable of increasing the sensitivity of the explosive to detonation and it should be sufficiently inexpensive and easy to handle to make it commercially useful. Prior art sensitizing materials sometimes fall short of these criteria.

It is therefore an object of the present invention to provide an improved chemical sensitizing agent for insensitive explosives thereby rendering them more useful.

It is another object to provide a chemical sensitizer for explosives which is inexpensive, compatible with explosives and liberates a high volume of gas per unit weight.

These and further objects of the present invention will become readily apparent from the following detailed description and specific examples.

Broadly, the present invention contemplates the use of a urea-formaldehyde-hydrogen peroxide reaction product (herein designated UFP) as a sensitizing agent for explosives. This UFP product is known to the art. While the precise chemical structure of the UFP product is not known, it possesses the empirical formula $C_3H_6N_2O_3$, and may be readily prepared by reacting urea, formaldehyde and hydrogen peroxide in the presence of concentrated (70-71%) nitric acid. The product is a white crystalline compound which melts with decomposition at 200° C. and is obtained in good yield using the method described above. This product is described in the literature by Griswold and Siegens in Berichte 47, pages 2464-9 (1914) and also in Berichte 54B, pages 492-8 (1921).

UFP is relatively insensitive to impact. However, I have found that if from about 5 percent to about 95 percent by weight of a relatively insensitive explosive like NH_4NO_3 is admixed with from about 95 percent to about 5 percent UFP and the mixture subjected to impact, the mixture will explode upon an impact less than that necessary to explode the explosive by itself.

Explosives with which the present UFP compounds may be effectively blended are:

Primary high explosives, such as mercury fulminate, lead azide, diazodinitrophenol, lead styphnate, nitromannite and the like; secondary high explosives, such as TNT

2

(trinitrotoluene, trimethylenetrinitramine), PETN (pentaerythritol tetranitrate), ammonium picrate, picric acid, ammonium nitrate, DNT (dinitrotoluene), EDNA (ethylenediaminedinitrate), NG (nitroglycerin), AN (ammonium nitrate, nitrostarch), and the like; low explosives such as smokeless powder, nitro-cotton, NG (nitroglycerine), black powder (potassium nitrate, sulfur, charcoal), DNT (dinitrotoluene) and the like. The preferred explosives are sodium nitrate, ammonium perchlorate, ammonium nitrate, TNT, and DNT.

UFP is also compatible and may be admixed with non-explosive ingredients commonly found with explosives such as aluminum, waxes, diphenylamine, metal nitrates, mononitrotoluene, ferrosilicon, wood pulps, meals, and other combustibles, paraffin, and other hydrocarbons, chalk, sulphur, carbon and the like.

The method of detonating mixtures of UFP and explosives, obviously depends upon the particular mixture. When the UFP is mixed with a primary high explosive, the explosive is initiated by simple ignition, by such means as spark, flame, impact, and other primary sources of heat. For mixtures of UFP and secondary explosives, the most practical manner of initiating an explosive is through the use of detonators or boosters.

The increased sensitivity to explosion which UFP imparts to relatively insensitive explosives is shown by the following examples.

EXAMPLE I

Preparation of UFP (urea-formaldehyde-hydrogen peroxide)

A 55 gallon stainless steel tank provided with agitation and a portable cooling unit was used as the reaction vessel.

The following were precooled and placed in the tank:

35 56.4 lbs. of 35% formaldehyde solution, UFP;
79.1 lbs. of 37% hydrogen peroxide solution, C.P.;
20.4 lbs. of urea, UFP.

The mixture was stirred until the urea was completely dissolved and cooled until the temperature reached 5° C. Concentrated nitric acid (reagent grade) was slowly added to the mixture with stirring. After 5 pints of acid were added, reaction and precipitation began. After the addition of 38 pints of acid, the temperature was 28° C. After this acid addition the mixture was stirred for 2 hours, and then diluted 50% with water. The mixture was allowed to stand for 48 hours, then filtered and washed free of acid.

EXAMPLE II

Drop test for explosive sensitivity

This test was conducted using the U.S. Bureau of Explosives drop test apparatus, using a two kilogram drop weight and a 10 milligram sample.

55 All mixtures were oxygen balanced, that is, sufficient oxygen was present to convert carbon and hydrogen present to CO_2 and H_2O respectively. Each test value was determined on the basis of a minimum of 20 individual tests.

60 In these sensitivity tests PETN was used as a comparison as no other commonly used secondary explosive is more sensitive.

In Table I are the results of mixtures of UFP and AP (ammonium perchlorate). These mixtures of UFP-AP and aluminum are similar to composite propellants. The results show that UFP and ammonium perchlorate react readily.

The table also shows that the mixtures of UFP and ammonium perchlorate are more sensitive than mixtures of ammonium perchlorate and other organic materials. An unobvious result was that UFP influenced sensitivity more than DNT (dinitrotoluene), an explosive itself.

TABLE I.—DROP TEST SENSITIVITY OF UFP AND AMMONIUM PERCHLORATE MIXTURES

Mix composition:	50% drop height ¹ (in.)
PETN	3.3-3.7
Ball powder	5.8
Ammonium perchlorate (AP)	10.0
UFP	30.0
UFP 25%-AP 75%	3.3
UFP 40.5%-AP 59.5%	3.5
UFP 23%-AP 67%-powdered aluminum 10%	10
Dinitrotoluene (oil) 19%-AP 81%	4.0
2,4-dinitrotoluene 19%-AP 81%	9.3
UFP 20%-trinitrotoluene (TNT) 60%-powdered aluminum 20%	12.0
UFP 25%-AP 75% = 95%-polyoxymethylene 5%	20.0
	15
	4.0-5.7

¹ The distance through which a 2 kg. weight must fall to cause explosion in 50% of the trials.

In Table II are the results of UFP-ammonium nitrate mixes. These results show the UFP-ammonium nitrate composition to be more sensitive than the ammonium nitrate starch blend.

TABLE II.—DROP TEST SENSITIVITY OF UFP AND AMMONIUM NITRATE BLEND

Mix composition:	50% drop height ¹ (in.)
PETN	3.3-3.7
Ball powder	5.8
UFP 33%-ammonium nitrate 67%	5.8
Starch 16%-ammonium nitrate 84%	20.0
UFP 37%-sodium nitrate 63%	9.5

¹ The distance through which a 2 kg. weight must fall to cause explosion in 50% of the trials.

EXAMPLE III

Detonability of UFP mixes

Blends of UFP and explosives were tested/or detonated using (50/50 PETN/TNT) boosters. Measurement of the detonation velocity and pressure were made. The results are shown in Table III.

TABLE III

Mix Composition	Density, gm./cc.	Velocity, m./sec.	Pressure, Kilobars
Dinitrotoluene	0.95	2,500	15
Ammonium nitrate; Fuel Oil	0.80	2,500	13
UFP, 25%; Ammonium nitrate, 75%	0.88	2,400	12
UFP, 23%; Ammonium nitrate, 67%; Powdered aluminum, 10%	0.93	3,110	25
UFP, 33%; Ammonium nitrate, 67%	0.79	3,120	29

These results show that UFP is superior to fuel oil, a sensitizer for ammonium nitrate.

I claim:

1. An explosive composition comprising a sensitizing amount of a sensitizing agent having an empirical formula $C_3H_6N_2O_3$ obtained by reacting urea, formaldehyde, and hydrogen peroxide in the presence of nitric acid, said sensitizing agent melting with decomposition at 200° C., and an explosive selected from the group consisting of ammonium perchlorate, ammonium nitrate, sodium nitrate, and trinitrotoluene.

2. A composition as described in claim 1, wherein the amount of the sensitizing agent is from about 5-95 weight percent and the amount of said explosive is from about 95-5 weight percent.

3. An explosive composition comprising a sensitizing amount of a sensitizing agent having an empirical formula $C_3H_6N_2O_3$ obtained by reacting, urea, formaldehyde, and hydrogen peroxide in the presence of nitric acid, said sensitizing agent melting with decomposition at 200° C., an explosive selected from the group consisting of ammonium perchlorate and trinitrotoluene, and a powdered metal, said metal having a particle size of from about 25-75 microns.

4. The composition as described in claim 3, wherein said metal is aluminum.

5. A method of sensitizing explosives which comprises adding a sensitizing amount of a sensitizing agent having an empirical formula $C_3H_6N_2O_3$, obtained by reacting urea, formaldehyde, and hydrogen peroxide in the presence of nitric acid, said sensitizing agent melting with decomposition at 200° C., to an explosive selected from the group consisting of ammonium perchlorate, ammonium nitrate, sodium nitrate and trinitrotoluene.
